CLAIM

The ornamental design for a cushion with storage pockets, as shown and described.

DESCRIPTION

FIG. 1 is an environmental perspective view of a cushion with storage pockets showing my new design, the portion of the figure shown in broken lines being for illustrative purposes only and forming no part of the claimed design; FIG. 2 is an enlarged front elevational view thereof; FIG. 3 is an enlarged rear elevational view thereof; FIG. 4 is an enlarged top plan view thereof; FIG. 5 is an enlarged left side elevational view thereof, the right side being a mirror image of that shown; and, FIG. 6 is a bottom plan view thereof. The cross hatching represents conventional fabric and is understood to extend throughout the areas represented.
